(57) **CLAIM**

What is claimed is the ornamental design for a tape dispenser, as shown and described.

DESCRIPTION

FIG. 1 is a perspective view of a tape dispenser, showing the new design with a lid thereof in an open position;

FIG. 2 is a perspective view thereof, illustrated with the lid in a closed position;

FIG. 3 is a front elevational view thereof;

FIG. 4 is a rear elevational view thereof;

FIG. 5 is a left-side elevational view thereof, the lid illustrated in the closed position, the right-side elevational view being a mirror image thereof;

FIG. 6 is a top plan view thereof, the lid illustrated in the closed position;

FIG. 7 is a bottom plan view thereof, the lid illustrated in the closed position;

FIG. 8 is a perspective view of the container portion of the design shown separately for completeness of illustration.

FIG. 9 is a top plan view thereof;

FIG. 10 is a bottom perspective view of the lid portion of the design shown separately for completeness of illustration; and,

FIG. 11 is bottom plan view of the lid thereof.

The broken lines showing a hand and tape in FIG. 1 are included for the purpose of illustrating the invention in use, and form no part of the claimed design.
